MARINE PROPELLER

Bert O. Godfrey, Brooklyn, N. Y.

Application September 29, 1951, Serial No. 248,911

7 Claims. (Cl. 170—160.12)

1

There is a type of marine propeller which is especially designed for use with an auxiliary in-board engine of a sail boat. In order to lessen the drag of the propeller during sailing, the blades of such propellers are arranged to fold automatically into a trailing position with respect to the hub, this action occurring primarily as a result of the relative aftward movement of the water past the blades during nonpowered forward movement of the craft. Whenever it is desired to apply power through such a folded propeller, rotation of the shaft and the propeller hub will start the blades outwardly by the action of centrifugal force upon the blades, whereupon continuance of the rotation will develop a slight thrust forwardly by the reaction of the blades aftwardly against the water, and this will urge the blades fully outwardly against stops into a normal outflung position of use, wherein they will remain as long as such rotation and forward propulsive thrust continues. Whenever rotation of the propeller ceases, the blades will fold down under the influence of the relative aftward movement of the water past the blades, as the boat glides forwardly.

It becomes evident that there would be no such relative aftward movement of water past the blades if it were attempted to reverse the propeller to back the boat from a standing start, for instance, away from a dock. To my knowledge the only way that such propellers can effect powered aftward movement is to rotate the propeller at a sufficiently high speed that the centrifugal effect on the blades will hold them somewhat outwardly and produce some—even if a very slight—aftward thrust on the craft, as compared to the normal forward propulsive thrust. This is a very unsatisfactory and wasteful way by which the objective can but lamely be accomplished.

It is the primary object of the present invention to provide means for use with such propellers which will lock the blades in outflung position, and hold them there, even after cessation of rotation of the propeller, for a brief period of time, so that during that period the sense of rotation can be reversed, and when reversed—the blades remaining locked in position—will develop full aftward thrust. However, since the unlocking is retarded during but a brief period of time, to all practical intents and purposes the blades will fold down into trailing position of disuse automatically following either aftward or forward powered movement, as soon as nonpowered forward movement reoccurs.

2

The general object of this invention has already been indicated. It is a further object to provide mechanism of this nature which shall be compact, inexpensive, simple in construction and in action, and reliable, operating wholly automatically and without more than passing attention on the part of the pilot. It is also an object to provide in such mechanism simple means for retarding initial disengagement of the locking elements, yet devices to this end of such nature as will not appreciably retard eventual disengagement, nor effective engagement of the locking elements at any time.

My invention comprises a novel propeller and a novel automatic locking and unlocking arrangement employed in conjunction with the parts of the propeller, all as shown in the accompanying drawings, and as will be described and claimed hereinafter.

20 Figure 1 is a view in the axial direction, with the hub transversely in section.

Figure 2 is in part a section, and in part an elevation of the hub.

25 Figure 3 is an enlarged sectional detail of the locking elements and the means to retard their disengagement initially.

On the propeller shaft 1 is mounted the recessed hub 2, in any suitable manner, its form and manner of mounting being immaterial. The propeller illustrated is shown as having two blades 3, each of which is formed with a flat root portion 4, which is pivotally mounted at 5, upon an axis arranged chordwise within the hub 2. Each such blade may swing into a trailing position of disuse about the pivot at 5, or by water reaction when rotated may be urged outwardly against a fixed stop 6 into its outflung position of use.

The arrangements so far described are known, but it is not essential that these particular forms and arrangements be employed, and they are chosen merely as typical.

40 Each blade root 4 is provided with a locking element, such as the recess 7, and a complementary locking element is carried by the hub, such as the locking pin 8 mounted in a bore in the hub which parallels the pivot means at 5. These locking pins 8 are shiftable in the direction of their length, and each is so located that when the corresponding blade 3 is in its outflung position, the locking pin 8 may engage within the locking recess 7 of that blade.

45 Such movement of the locking pin 8 is accomplished under the influence of a centrifugal mass 9 pivoted at 10 within a recess of the hub, and 50 having a finger 11 which engages within a notch

12 of the locking pin 8, to shift the latter. The arrangement is such that when the centrifugal mass is retracted in its inward position, shown in dash lines in Figure 1, the locking pin is withdrawn from locking engagement, whereas when the centrifugal mass 9 is centrifugally thrown outwardly to the full extent, the locking pin will have been moved into locking engagement, as it is shown in full lines in the same figure.

It is preferred that resilient means such as a spring 13 be employed, so arranged as to urge the centrifugal mass into its inward position, and consequently acting also to urge the locking pin 8 into its disengaged position. The locking means are thereby urged always, except when under the influence of centrifugal force acting on the masses 9, into unlocked position, leaving the blades 3 free to move to their trailing position. If the blades are in their trailing position, the springs will not be of sufficient strength to prevent the blades' moving into their outflung positions of use, when acted on by centrifugal force and by water reaction.

In order to insure that the locking elements will not disengage immediately upon cessation of the rotation of the hub, time-delay means are employed. There are various ways of accomplishing this result, many of which would be suitable, and as an example of such an arrangement the exterior end of each bore, in which a locking pin is shiftable is closed by a plug 14, to provide a closed, liquid-filled space 15 variable in volume as the locking pin shifts therein. Admission thereto is through the angled passage 16 in this end of the locking pin 8 and a passage 17 in the hub. The relative positions of the registering portions of the passage 16 and the port 17 are such that there is no appreciable restriction until the locking pin approaches the end of its locking movement, and after it has already engaged within the locking recess 7. As it approaches the end of this movement, there is a restriction which slows down the movement. Correspondingly reverse or unlocking movement of the locking pin 8 is similarly retarded by the small size of the orifice between the passage 16 and port 17, but under the urging of the spring 13 the locking pin continues to withdraw, and after a brief or momentary retardation the locking pin moves freely again to its unlocked position.

In operation, the blades being unlocked, will swing downwardly about their pivots at 5 into the trailing position of disuse as shown in Figure 2 in dash lines, purely by the relative water movement accompanying forward nonpowered movement of the boat. Whenever powered forward propulsion is desired, rotation of the shaft 1 and hub 2 starts the blades outwardly by centrifugal action and the water reaction completes their outward movement. At the same time the centrifugal force urges the masses 9 outwardly about their pivots at 10, and the locking pins 8 will engage each within its locking recess 7, to lock the blades in their outflung position. This is not necessary during powered forward propulsion, nor is it objectionable. If, however, it is desired to reverse the propulsive effect, rotation of the hub 2 must cease, at least momentarily, as it goes through the reversal. Were it not for the locking elements and the delay in disengaging them, this reversal would merely act to permit collapse of the blades into their position of disuse. Since, however, the locking elements are still engaged, and do not disengage immediately upon cessation of rotation, but only after a

momentary pause, it follows that if the pilot will only be prompt in reversing the sense of rotation, the locking elements will be retained in their locked position of engagement, and consequently will enable powered reverse propulsion of the boat. Immediately reverse rotation commences, the masses 9 are thrown centrifugally outwardly again and the locking elements again come into full engagement, which continues as long as there is rotation of the hub, regardless of the sense of that rotation.

If it is desired to propel the boat aftwardly from a standing start, as when backing away from a pier, or after disengagement of the locking elements has permitted the blades to swing aftwardly, it is only necessary to start the propeller shaft forwardly briefly and momentarily, in order to fling the blades outwardly again and to lock them thus outflung, and then before there has been any appreciable forward propulsion, to reverse the shaft. It will be found that the blades have become locked in outflung position and will again give full rearward propulsive effect. The momentary forward rotation will have little effect on the boat, for it is so promptly propelled aftwardly.

Since the retention of the blades in outflung position is for only a brief moment following cessation of rotation, they will never remain locked in outflung position while there is any appreciable forward way maintained by the boat, nor long after rotation of the propeller shaft and hub ceases.

I claim as my invention:

1. In a marine propeller which includes a hub and blades mounted thereon for movement between a trailing position of disuse and an outwardly flung propulsive position of use, and urged into such position of use, at least in part, by the water reaction forces on the blades such as accompany forward propulsive rotation, means on the hub and means movable with the blade and positioned to register with said first means and to interengage with the latter when the blade is outflung, means automatically operable under the influence of the hub's rotation to urge said two interengageable means into engagement, and likewise under the influence of cessation of rotation to urge them out of engagement, and means operable automatically at cessation of rotation to retard momentarily the initiation of their disengagement.

2. In a marine propeller which includes a hub and blades pivotally mounted thereon, on chordal axes, to fold into trailing positions of disuse, or to swing outwardly upon such axes against stops into outflung water-reactive positions of use when the propeller is rotated for forward propulsion, means to lock said blades in such outflung positions preparatory to reverse rotation, said locking means including a locking element carried by each blade, and a complementary locking element shiftable mounted in the hub, in positions for interengagement when the blades are in their outflung positions, and a mass mounted on the hub for shifting under the influence of centrifugal force accompanying rotation of the hub, and operatively connected to said hub-mounted locking element to shift the latter into engagement with the blade-carried locking element, as a result of such rotation.

3. A marine propeller as in claim 2, including resilient means urging said centrifugal mass radially inwardly and its hub-mounted locking element towards unlocked position, and means to

retard such movements momentarily following cessation of the hub's rotation.

4. A marine propeller as in claim 2, wherein the hub-mounted locking element is formed as a pin received within a bore in the hub which parallels and is located a given radial distance from the chordal pivotal mount of the blade, and the complementary blade-carried locking element is formed as a recess in the blade's root at the same radial distance, and at a location to register with said pin when the blade is outflung.

5. A marine propeller as in claim 4, including an orifice located to cooperate with the pin, as the latter is shifted, and to be constricted by the pin during initiation of unlocking movement, to retard such unlocking movement momentarily.

6. In a marine propeller, in combination with a hub and with blades mounted and guided on said hub for relative movement between an outflung operative position and a trailing position of disuse, and for movement into such outflung position in part by centrifugal force and in part by water reaction accompanying forward propulsive thrust, and movable into such trailing position by relative aftward water movement accompanying nonpowered forward movement, a centrifugal mass mounted in the hub, a locking pin shiftably mounted in the hub adjacent and movable towards and from each blade, a complementary locking recess in each blade, located for engage-

ment by the corresponding locking pin when its blade reaches outflung position, an operative connection between said centrifugal mass and said pin, arranged to urge the pin into locking engagement within its locking recess, whenever rotation of the hub imposes a centrifugal force on said mass, and means to retard initial withdrawal of said pin from its recess, following cessation of rotation of the hub.

7. A marine propeller as in claim 6, including a spring arranged to return the centrifugal mass to its inward position upon cessation of the hub's rotation, and to shift the pin to disengaged position, following its initial retardation, except as centrifugal outward movement of the mass reoccurs promptly, as a result of resumption of rotation of the hub.
